UNITED STATES PATENT OFFICE

FRED CLAYDEN, OF FELTHAM, ENGLAND, ASSIGNOR TO EDWIN HENRY CHAMBERS, OF MAIDSTONE, ENGLAND, AND HERBERT EGERTON, OF LONDON, ENGLAND

CURB OR EDGING FOR GARDEN PATHS AND THE LIKE

Application filed May 19, 1930, Serial No. 453,754, and in Great Britain June 1, 1929.

This invention relates to improvements in curbs or edgings for garden paths and the like.

The object of the present invention is to produce a curb or edging which can be manufactured cheaply and with economy of material, is stable and easily inserted into and removed from the ground when desired, can be easily and quickly interlocked with, or unlocked from, adjacent curbs or edgings, and can be easily bent longitudinally to any desired shape or form.

According to this invention the curb or edging is made from sheet metal, one longitudinal edge being straight and the other having prongs of suitable length. After being cut to shape the sheet metal is corrugated transversely in such a manner that a prong coincides with each flute of the corrugations, so that an end view will show a double row of prongs, each offset from the longitudinal axis of the sheet by the depth of the corrugations.

Preferably, in order to economize material in the manufacture, a strip of sheet metal, of a length and width sufficient to provide two complete curbs, is divided by cutting it in a zig-zag fashion, thus leaving saw like prongs in each half. At one end of each curb a tongue is cut out longitudinally of the curb and at the opposite end a corresponding slot is cut.

The top edge of the curb may be beaded and a strengthening wire passed therethrough, and a further slot is cut at a suitable position in the curb for the purpose of allowing a cord or the like to pass therethrough to fasten the curbs together for packing and transport.

My invention is illustrated in the accompanying drawings in which:

Fig. 1 is a broken front elevation of a curb;

Fig. 2 is a top plan view of same; and

Fig. 3 is an end elevation.

The curb or edging has a body portion 1, having the upper edge 2 beaded, with a

strengthening wire 3 passed therethrough, and the lower edge formed into a series of prongs 4, each of which coincides with one of the flutes of the transverse corrugations.

At one end of the body portion two tongues 5 are cut longitudinally of the curb and at the opposite end two corresponding slots 6 are cut.

When the curb or edging is placed in position the tongues 5 pass through the slots 6 of the next adjacent curb and can be turned back on themselves to lock the two curbs together. This form of locking provides a means of ensuring that the two adjacent edges of the beading at the upper edge 2 of the curb fit closely together.

For convenience when packing curbs, each is provided with an additional slot 7 through which a cord or the like can be passed.

It will readily be understood from the description and drawings that a curb made in accordance with this invention provides, owing to the staggering of the prongs, a broad and firm base for inserting it into the ground, and that the corrugations, whilst permitting of longitudinal bending of the curb or edging, yet prevent bending across the depth. Also the method of interlocking is simple and efficient, and permits any curb to be easily and quickly removed and a fresh curb substituted as may be desired.

I claim:

1. A curb for garden paths and the like comprising a sheet of corrugated metal, and a prong for each flute of the corrugations formed on the lower edge of said sheet.

2. A curb for garden paths and the like comprising a sheet of corrugated metal, a prong for each flute of the corrugations formed on the lower edge of said sheet, and means for locking each curb to adjacent curbs.

3. A curb for garden paths and the like comprising a sheet of corrugated metal, a prong for each flute of the corrugations

formed on the lower edge of said sheet, and a tongue at one end of each curb and a slot at the other end of each curb to lock the curbs together.

4. A curb for garden paths and the like comprising a sheet of corrugated metal, a prong for each flute of the corrugations formed on the lower edge of said sheet, a tongue at one end of each curb and a slot 10 at the other end of each curb to lock the curbs together, and a beaded upper edge to the corrugated sheet and a strengthening wire passed therethrough.

In testimony whereof I have hereunto set 15 my hand this fifth day of May, 1930.

FRED CLAYDEN.
